UNITED STATES PATENT OFFICE.

CHARLES E. TURNER AND ROBERT LOFTON HYMAN, OF MACON, GEORGIA;
SAID HYMAN ASSIGNOR TO SAID TURNER.

TRUNK.

SPECIFICATION forming part of Letters Patent No. 787,236, dated April 11, 1905.

Application filed October 24, 1904. Serial No. 229,778.

To all whom it may concern:

Be it known that we, CHARLES E. TURNER and ROBERT LOFTON HYMAN, citizens of the United States, residing at Macon, in the county of Bibb and State of Georgia, have invented a new and useful Trunk, of which the following is a specification.

This invention relates to trunks, and has for its object to effect in a simple and convenient manner the automatic elevation of a tray by the opening of the lid of the trunk into such a position as to expose the open top of the trunk for access to the interior thereof, while at the same time supporting the tray in position for access thereto.

Another object of the invention is to provide for supporting and elevating a supplemental tray beneath the main tray and to provide for drawing said supplemental tray outward into position for access thereto and also to permit entire removal of the supplemental tray whenever desired without requiring any disconnection of the parts of the elevating means.

It is also designed to provide for the convenient removal of the main tray without interfering with any of the parts of the elevating means.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a sectional view taken transversely across one end of a trunk with the tray-supporting means of the present invention in position to support a main tray and a supplemental tray in an elevated position. Fig. 2 is a similar view showing the trunk-lid closed with the trays in their lowermost positions. Fig. 3 is a cross-sectional view on the line 3-3 of Fig. 2. Fig.

4 is an enlarged detail sectional view on the line 4-4 of Fig. 2.

Like characters of reference designate corresponding parts in each and every figure of the drawings.

Preparatory to explaining in detail the construction of the present invention it will here be stated that duplicate tray supporting and elevating devices are employed, one at each end of the trunk, with each device pivotally supported upon the body of the trunk and connected to the lid or cover for actuation thereby to raise and lower the trays with the opening and closing of the lid or cover, and therefore an explanation of one of the devices also applies to the other.

The present invention has been specially prepared with a view of application to any ordinary form of trunk, a conventional form of which has been shown in the drawings and designated 1, with the usual hinged lid or cover 2. Within the trunk and in close proximity to each end thereof are two substantially parallel bars 3 and 4, having individual pivotal connections 5 and 6 with the adjacent end of the trunk-body, there being washers 7 and 8 interposed between the bars and the end of the trunk. A cross-bar 9 has its opposite ends pivotally connected to the upper ends of the bars 3 and 4, as at 10 and 11, whereby the bars are connected and remain in parallelism during their swinging movements upon the pivotal supports 5 and 6. In the upper edge of the cross-bar 9 are notches or depressions 12, for a purpose as will hereinafter appear. A link 13 is pivotally connected to the pivot-pin between the bar 3 and the cross-bar 9, the upper end of the link 13 being pivotally connected to the inner side of the adjacent end of the lid of the trunk, as at 14, whereby the bars 3 and 4 will be simultaneously swung up and down upon their pivotal supports 5 and 6 by the opening and closing of the lid or cover of the trunk. It will here be explained that the three bars and the link are of metal, and thereby comparatively thin, so as to afford the maximum clear space between the ends of the trunk.

The usual main tray 15 of the trunk is provided at each end with headed bearing projections 16 for engagement with the respective notches or seats 12 in the cross-bar 9, whereby the tray moves up and down with the bar and is maintained in a substantially horizontal position throughout its movements. By having the seats or notches 12 open at their tops the main tray may be readily lifted from the opposite bars 9 without interfering in any manner whatsoever with the elevating devices.

In addition to the main tray 15 it is proposed to provide a comparatively shallow supplemental tray 17, particularly designed for containing skirts, and in each end of this supplemental tray there is provided a longitudinal groove or way 18, which is closed at its front end and opens through the back of the tray. The purpose of this guideway is to receive the projections 19 and 20, carried by the bars 3 and 4, with the projection 20 located a slight distance above the projection 19, thereby to tilt upwardly the front end of the tray when the lid of the trunk is open in order that the tray may clear the top edge of the front of the trunk-body when drawn out from beneath the upper main tray 15 when it is desired to have access to the supplemental tray 17. By having the guideway 18 open at its rear end the projections 19 and 20 may be readily entered and removed through said open end, or, to be more correct, the tray 17 may be readily engaged and disengaged with respect to the projections. While the supplemental tray is capable of being entirely removed from the trunk, access may be had thereto without removing the tray by drawing it forwardly until it can rest upon the top of the front edge of the front body, in which position it will be projected sufficiently in front of the upper tray 15 to permit convenient access to the top of the supplemental tray.

With the trunk closed, as in Fig. 2, when the lid or cover is opened, as in Fig. 1 of the drawings, the link 13 operates to swing the bars 3 and 4 upwardly, thereby elevating the two trays, the latter being maintained in substantially horizontal positions during their upward movements and the parts being so proportioned as to bring the back of the lower supplemental tray into contact with the back of the trunk-body, thereby to automatically project the lower supplemental tray in front of the upper tray 15. When the lid or cover of the trunk is open, the two trays will be elevated to positions above the top of the trunk by the operation of opening the lid, and the trays are supported in positions for access thereto, thereby obviating the necessity of individually lifting the trays out of the trunk and placing the same upon the floor or other support in order that access may be had thereto and to the interior of the body of the

trunk. Upon closing the lid the bars 3 and 4 will be swung downwardly to the positions shown in Fig. 2, the front end of the supplemental tray 17 being beveled or rounded, as at 21, for contact with the top edge of the front of the trunk-body, so as to arrest the forward movement of the tray and guide the latter downwardly into the body of the trunk, while the projections 19 and 20 slide forwardly in the guideway 18 to accommodate for this movement of the lower supplemental tray.

From the foregoing description it will be understood that the present invention may be applied to any ordinary trunk and has been constructed for application directly to the ends of the trunk and the ends of the lid without requiring any additional supports rising from the bottom of the trunk and projected from the ends thereof, whereby the two elevating devices will accommodate the maximum length of the tray which the trunk-body is capable of containing. Moreover, the device may be fitted in place without changing the trunk in any manner whatsoever, and when in place does not take up any unnecessary room, nor is it liable to injure the contents of the trunk.

Having fully described the invention, what is claimed is—

1. The combination with a trunk-body having a hinged lid, of tray-elevating devices at each end of the trunk and consisting of a pair of swinging bars pivotally supported upon the trunk and provided with lateral projections, a link connected to the lid and to the swinging bars, and a tray provided at each end with a guideway slidably receiving the projections of the swinging bars.

2. The combination with a trunk-body having a hinged cover, of tray-elevating devices at opposite ends of the trunk, each device comprising a pair of swinging bars pivotally supported upon the trunk-body and provided with lateral projections, the projection of the front bar being disposed above that of the rear bar, a link connecting the lid and the swinging bars, and a tray provided at each end with a guideway slidably receiving the projections, the front of the tray being inclined upwardly in its elevated position.

3. The combination with a trunk-body having a hinged cover, of tray-elevating devices at opposite ends of the trunk, each device comprising a pair of swinging arms pivotally supported upon the trunk-body and provided with lateral projections, means connecting the arms with the lid, and a tray having each end provided with a guideway slidably receiving the projections, the rear end of the guideway being open for the reception and removal of the projections.

4. The combination with a trunk-body having a hinged lid, of tray-elevating devices at opposite ends of the trunk, each device being

5 pivotally supported upon the trunk-body and connected with the lid, and a tray having a slidable connection with the respective elevating devices, the tray being disposed for engagement with the front of the trunk during the closing of the lid to slide the tray rearwardly upon the elevating devices and permit of the tray entering the trunk.

10 5. The combination with a trunk having a hinged lid, of tray-elevating devices at opposite ends of the trunk, each device being pivotally supported upon the trunk-body and connecting with the lid for simultaneous movement therewith, an upper tray detachably supported upon the elevating devices, and a lower tray slidably and detachably carried by the elevating devices and located below the upper tray.

15 6. The combination with a trunk having a hinged lid, of a pair of vertically-swinging bars pivotally supported upon each end of the trunk, projections carried by the bars inter-

mediate of their ends, a cross-bar pivotally connecting the upper ends of the swinging bars and provided in its upper edge with a pair of notches, a link pivotally connected to the lid and to the rear swinging bar, an upper tray provided at each end with a pair of projections detachably received within the respective notches of the cross-bar, and a lower tray having a longitudinal slot in each end thereof and slidably receiving the adjacent projections, the rear end of the slot being open for the entrance and removal of the projections.

20 In testimony that we claim the foregoing as our own we have hereto affixed our signatures in the presence of two witnesses.
